ULTRA SHORT WAVE CONDUCTOR

Mendel Osnos, Berlin, Germany, assignor to Tele-funkens Gesellschaft fur Drahtlose Telegraphie m. b. H., Berlin, Germany, a corporation of Germany

Application June 30, 1932, Serial No. 620,279
In Germany July 27, 1931

5 Claims. (Cl. 250—36)

This invention relates to an improved ultra short wave conductor.

An object of this invention is to provide a conductor which is particularly adapted to short 5 wave circuits, such as, for example, a Barkhausen ultra short wave oscillator.

According to the invention disclosed in German Patent No. 515,472, corresponding to United States Patent No. 2,031,846, granted February 25, 10 1936, in order to render the frequency of oscillation independent of the temperature, the conductor parts of the oscillator circuits are formed in such a way that the surface of an insulation body having a temperature coefficient of expansion of negligibly small value, such as quartz, glass, 15 quartz-glass, porcelain, or the like, are completely or partly coated with metal. Experiments have shown that apparatus thus built exhibit rather large damping for very short waves.

20 The present invention is an improvement on United States Patent No. 2,031,846, supra, and is based upon an understanding that such undue damping is not so much due to the additional losses of current occasioned by skin effect, but 25 rather by the dielectric losses of the insulation body. In the light of this discovery the insulation body having a metallic coating according to this invention is made tubular. The tube may have the shape of a rod, or of a flat or cylindrical spiral 30 or the like.

Referring now to the drawing, 1 and 2 represent the improved tubular conductor of this invention comprising an insulation body of the class described above having a temperature coefficient of negligible value and coated by a highly conductive layer of metal, such as silver in a Barkhausen oscillator circuit, 3 and 4 indicate fixed condensers, 5 the grid of an oscillator tube, 6 the plate of the oscillator tube, 7 and 8 are the 35 40 coupling transformer windings, 9 indicates a grid battery, and 10 the filament heating battery, 11 the filament resistor, and 12 the filament of the oscillator vacuum tube.

While the showing of this improved conductor 45 is shown and described as a conductor employed

in a high frequency oscillator circuit, it is to be understood that it is capable of use in other forms, such as an inductance or choke coil, within the spirit and scope of the appended claims.

I claim:

1. In an ultra short wave circuit, an electron discharge device oscillator and a conductor in circuit with said oscillator comprising a tubular insulating body of non-conducting material possessing a negligibly low temperature coefficient 10 and a continuous layer of highly conducting material superposed on said insulating material.

2. A circuit as defined in claim 1 characterized in this that said conducting material comprises silver.

3. An ultra high frequency oscillation circuit comprising a short wave electron discharge device oscillator with whose electrodes are coupled electrical conducting elements having a tubular base of hard, solid, non-conducting material possessing an extremely small coefficient of thermal expansion and a continuous layer of highly conducting material superposed on said tubular base.

4. In combination, a short wave electron discharge device oscillator having an anode, cathode 25 and grid, current supply means for maintaining said grid at a high positive potential relative to said anode and cathode whereby pendular motion of electrodes is obtained about said grid in the Barkhausen-Kurz manner, a conductor coupled 30 to said grid and a conductor coupled to said anode, said conductors comprising tubular insulating bodies of non-conducting material possessing negligibly low temperature coefficients and a continuous layer of highly conductive material 35 superposed on said insulating material.

5. In a radio frequency oscillation circuit, an electron discharge device having an electrode to which is coupled a conductor adapted to be traversed by the high frequency currents, said conductor having a hollow core of material of a low coefficient of thermal expansion and a continuous layer of highly conductive material superposed on and fixed to said core.

MENDEL OSNOS. 45
